UNITED STATES PATENT OFFICE.

CHARLES P. SMITH, OF MARINE CITY, MICHIGAN.

ATTACHMENT FOR LAMP-BURNERS.

1,103,696.

Specification of Letters Patent.

Patented July 14, 1914.

Application filed September 29, 1911. Serial No. 651,939.

To all whom it may concern:

Be it known that I, CHARLES P. SMITH, a citizen of the United States, residing at Marine City, in the county of St. Clair and State of Michigan, have invented new and useful Improvements in Attachments for Lamp-Burners, of which the following is a specification.

My invention relates to an attachment for lamp burners.

An object of my invention is to provide an attachment for lamp burners or the like which prevents the lamp chimney from being smoked, and at the same time gives a bright light.

Another object of my invention is to provide an attachment for lamp burners which can be easily inserted under the burner cap of the burner and one which will spread the flame from the wick of the lamp so as to give the same a greater brightness.

A still further object of my invention is to provide an attachment for lamp burners or the like which can be stamped from a single sheet of metal thereby obviating all unnecessary costs whatsoever in manufacturing the same, being merely bent at certain places to form my attachment.

With the foregoing and other objects in view, my invention relates to such details of construction and in the arrangement and combination of parts as will be hereinafter fully described and specifically pointed out in the appended claims.

In describing my invention in detail, reference will be had to the accompanying drawings wherein like characters denote like or corresponding parts throughout the several views and in which:—

Figure 1 is a side elevation of the lamp burner the burner cap being shown thrown open and my attachment being attached to said burner. Fig. 2 is a top plan view of my attachment. Fig. 3 is a bottom view of my attachment. Fig. 4 is a plan view of the blank form before the same has been bent to form my attachment.

In carrying my invention into practice I provide a single piece of sheet metal 1 which is adapted to be stamped so that an opening 2 will be formed near the center thereof, as clearly shown in Fig. 4 this opening has slight extensions 3 at each end thereof for a purpose that will be hereinafter fully described. Cut out portions 4 along both side edges are also formed during the

manufacture of the same. Said openings 2 and 3 and the cut out portions 4 may be formed at a single impression of a die or other cutting member. The member 1 is 60 bent at opposite ends upwardly, as shown in Fig. 1, so as to provide a base to rest upon a burner device or body 6 separate therefrom, and so that said ends or riser portions will terminate adjacent the top of 65 the wick or other burner member 5, which is suitably supported by said burner 6. Said upwardly projecting ends or riser portions are also bent or curved as shown to permit a cap, presently to be referred to, to fit or 70 close thereover. Pivoted to the burner body 6 is the usual burner cap 7 which when closed completely covers the attachment.

As will be realized, opening 2 is enlarged with respect to the burner member 5 in 75 order to provide for the admission of air to the burner member from below.

It will be readily seen that when the ends of my attachment are in a position as shown in Fig. 2 they will tend to spread the flame 80 which rises from the wick 5 so that the same will give much more light and at the same time will not smoke the chimney.

I desire to lay great stress upon the fact that my device is constructed from a single 85 piece of sheet metal and can be formed by the single impression of a die or other cutting member. It is also thought that it will be appreciated that my device can be manufactured at a very low cost.

I desire it to be understood that I may make slight changes in the construction and in the arrangement and combination of parts without departing from the spirit of my invention, provided such changes fall 95 within the scope of the appended claims.

Having thus fully described my invention, what I claim as new and desire to secure by Letters Patent is:—

1. In combination with a burner body, a 100 burner member and an adjustable cap, an attachment for the purpose specified separate from said body and member and having a base portion resting on said burner body provided with an opening through which 105 said burner member extends, said opening being enlarged with respect to the burner member to provide for the admission of air through the opening, said opening also having an extension in which the burner member is positioned, riser portions extending upwardly from said base portion on oppo- 110

site sides of the burner member and each terminating short of and adjacent said burner member, and said riser portions being shaped to permit said cap to close thereover.

2. In combination with a burner member, an attachment for the purpose specified formed as an integral metallic article, said attachment provided intermediate its end edges with an opening through which said burner member extends, said opening being enlarged with respect to the burner member to provide for the admission of air through the opening, and said attachment having a plurality of notches along opposite sides for the purpose specified.
- 10 3. In combination with a burner member,

an attachment for the purpose specified formed of a blank of metal, said blank provided intermediate its end edges with an 20 opening through which said burner member extends, said opening being enlarged with respect to said burner to provide for the admission of air through the opening, said opening having a plurality of extensions in 25 which said burner member is located and positioned, said blank having a plurality of notches along opposite sides for the purpose specified.

CHARLES P. SMITH.
